UNITED STATES PATENT OFFICE.

JOHN HAYES, OF BELLE VERNON, PENNSYLVANIA.

INTERNAL-COMBUSTION ENGINE.

Application filed March 1, 1922, Serial No. 540,218. Renewed May 24, 1924.

To all whom it may concern:

Be it known that I, JOHN HAYES, a citizen of the United States, residing at Belle Vernon, in the county of Fayette and State 5 of Pennsylvania, have invented certain new and useful Improvements in Internal-Combustion Engines, of which the following is a specification, reference being had to the accompanying drawings.

10 This invention relates to certain improvements in internal combustion engines and it is an object of the invention to provide a device of this general character constructed in a novel and improved manner whereby 15 the same is balanced in a manner to materially reduce vibration when the engine is in operation.

It is also an object of the invention to provide a novel and improved engine of this 20 type wherein the control of the ignition system is effectively maintained and wherein the engine is caused to operate with a maximum of power.

Another object of the invention is to provide an engine of this general character with 25 novel and improved means whereby the intake of the explosive charge or mixture is obtained in proper timed sequence and also wherein a make and break mechanism for 30 the ignition system is caused to function as required.

An additional object of the invention is to provide a novel and improved engine of this 35 type comprising a plurality of series of power units, each series coacting with a common shaft, together with means for transmitting the force of all of the shafts to a rotatable member common thereto.

Furthermore, it is an object of the invention 40 to provide a novel and improved engine of this type constructed in a manner whereby ready access may be had to the various parts comprised therein to facilitate repair and replacement.

45 The invention consists in the details of construction and in the combination and arrangement of the several parts of my improved internal combustion engine whereby certain important advantages are attained 50 and the device rendered simpler, less expensive and otherwise more convenient and advantageous for use, as will be hereinafter more fully set forth.

55 The novel features of my invention will hereinafter be definitely claimed.

In order that my invention may be the better understood, I will now proceed to describe the same with reference to the accompanying drawings, wherein:

Figure 1 is a view in top plan of an engine constructed in accordance with an embodiment of my invention; 60

Figure 2 is a view in side elevation of the device as herein disclosed;

Figure 3 is a longitudinal vertical sectional view taken through the engine as herein set forth and to one side thereof; 65

Figure 4 is a transverse vertical sectional view taken through my improved engine as herein embodied; 70

Figure 5 is an enlarged fragmentary view partly in section and partly in elevation illustrating a valve mechanism for controlling the inlet of fuel within a cylinder;

Figure 6 is a fragmentary view in bottom 75 plan of the structure illustrated in Figure 5; and

Figure 7 is an enlarged sectional view taken substantially on the line 7-7 of Figure 1, illustrating in detail the means for 80 operating the make and break mechanism comprised in the ignition system.

As disclosed in the accompanying drawings, B denotes a base of desired dimensions and configuration and which has bolted or 85 otherwise secured thereon a block A. The block A is cast to provide two parallel series of vertically disposed cylinders C, the cylinders of the series being of equal number with the cylinders in each series a multiple of 90 two.

Rotatably supported below each series of cylinders C is a crank shaft 1, the cranks 2 of said shaft being arranged in pairs with the cranks 2 of each pair having the same throw 95 and arranged in parallelism. The pairs of cranks are in such relative angular relation as required. It is also to be understood that the corresponding pairs of cranks 2 associated with both of the shafts 1 are complementary so that four pistons 3 working within both the series of cylinders travel in unison and in the same direction. By this means, a maximum power is assured with a minimum of vibration. 100

H denotes a head common to the cylinders C of both series and which head is provided with the inlet ports 4 each of which is in communication with a cylinder C. The ports 4 of each series of cylinders C are in com- 110

munication with an intake manifold M common to the ports 4 of a single series. The inner end portion of each of the ports 4 is formed into a valve seat 5 with which coacts a valve 6. The valve 6 has extending outwardly and radially therefrom an arm or lug 7 which is also connected with the lower or inserted end portion of a rod 8. When the valve 6 is seated or in closed position, the 10 arm or lug 7 seats within a notch or recess 9 provided in the inner face of the head H immediately adjacent the inner end of the port 4.

The rod 8 extends upwardly and freely 15 through an opening 10 formed in the head H and the outer or extended end portion of the rod 8 is secured to the end portion of a cross member 11. Each cross member 11 has secured thereto the rods 8 associated 20 with the valves 6 arranged in the cylinders C wherein each set of four pistons has unitary and corresponding travel, as is clearly indicated in Figures 1 and 3.

In communication with the cylinders C of 25 each series is an exhaust manifold E, the point of connection between the manifold and each cylinder being adjacent the head H, as is clearly illustrated in Figure 4. Each exhaust passage is normally closed in a well 30 known manner by a tappet valve 12, the stem 14 of which extends below the cylinder C. Coacting with the stem 14 is an expansible member or spring 15 which constantly urges the valve 12 to its seat.

The opposite end portions of the shafts 1 extend exteriorly of the block A or the base B and each of said end portions is in 35 driving connection, as at 16, with the transversely disposed shafts 17. One of the shafts 40 17 has its central portion in driving connection, as at 18, with a longitudinally disposed shaft 19 carrying a fly or balance wheel 20 and from which power may be transmitted through the gear 21 or the like also fixed 45 to said shaft. The second shaft 17 has its opposite end portions in driven connection, as at 22, with the outwardly directed shafts 23. These shafts 23 may be employed to 50 transmit power to the propeller shafts of an aeroplane or for any other purpose which may be desired.

Rotatably supported by the lower portion 55 of the block A below each series of stems 14 is a cam shaft 24 having fixed thereto the cams 25 each of which cams coacts with a stem 14. The cams 25 are so arranged to effect the desired opening of the valves 12 in proper sequence. Each of the shafts 24 is in driven connection, as at 26, with a shaft 1 so that the valve 12 will be caused to open in desired timed sequence.

Rotatably supported by the head H and 60 extending longitudinally thereof above the members 11 is a cam shaft 27 provided with the cams 28 which engage the cross mem-

bers 11 in proper timed sequence to effect the desired opening of the valves 6 and said shaft 27 is in driven connection, as at 29, with one of the shafts 1. Each of the members 11 has freely disposed therethrough the 70 upstanding pins or shanks 30, said pins or shanks 30 above each of the members 11 being provided with a head or enlargement 31. Interposed between each of the members 11 and head H and encircling the pins 75 or shanks 30 are the expansible members 32 herein disclosed as coiled springs which operate to constantly urge the valves 6 toward their seats 5.

The head H also has in communication 80 with each of the cylinders C an opening 33 in which is arranged a spark plug 34, the operating circuit for which is normally open. Extending longitudinally of the head H adjacent each pair of complementary cylinders 85 C is a rock arm 35 supported between a pair of upstanding lugs or bearings 36. The arm 35 has a pair of inwardly directed arms 37 provided in their outer ends with the contact members 38.

Substantially midway its length, the rock arm 34 is provided with an outstanding lug or arm 39 with which is engaged an extremity of a retractile member or coiled spring 40, the opposite end portions of said member or spring being anchored, as at 41, to the head H. The retractile member or spring 40 serves to constantly rock the arm 35 in a direction to maintain the contact members 38 in an inoperative position. Upon depression of the arms 37, the contact members 38 are adapted to have requisite electrical connection with the spark plugs so that the requisite firing will be had as required.

Transversely opposed arms 35 operate in unison and in a manner to cause simultaneous firing of the plugs 34 associated with the four cylinders C in which the pistons 3 have unitary and corresponding movement. In 110 order to effect this simultaneous movement of the arms 35, the central portions of said arms are provided with the inwardly directed lugs 42. Pivotaly connected with these opposed lugs 42 are the end portions of a 115 cross member 43. Extending outwardly from the central portion of each of the members 43 is an arm 44 continued by an upstanding extension or finger 45. This finger 45 is positioned directly below a cam 46 carried by the shaft 27 so that, upon rotation of the shaft 27, the cross member 43 will be forced downwardly in proper timed sequence to close the ignition circuits for the four associated cylinders C.

From the foregoing description it is thought to be obvious that an internal combustion engine constructed in accordance with my invention is particularly well adapted for use by reason of the conven-

ience and facility with which it may be assembled and operated, and it will also be obvious that my invention is susceptible of some change and modification without departing from the principles and spirit thereof and for this reason I do not wish to be understood as limiting myself to the precise arrangement and formation of the several parts hereing shown in carrying out my invention in practice except as hereinafter claimed.

I claim:

1. In an internal combustion engine, a cylinder, a head therefor, an inlet port disposed through the head, a valve working within the cylinder and coacting with the inner end of the port, a rod slidably disposed through the head adjacent to the port, and an arm connecting the inserted end por-

tions of the rod and the valve, said arm being radial with respect to the valve.

2. In an internal combustion engine, a cylinder, a head therefor, an inlet port disposed through the head, a valve working within the cylinder and coacting with the inner end of the port, a rod slidably disposed through the head adjacent to the port, and an arm connecting the inserted end portions of the rod and the valve, said arm being radial with respect to the valve, the inner face of the head immediately adjacent the inner end of the port being provided with a recess to receive the arm when the valve is in closed position.

In testimony whereof I hereunto affix my signature.

JOHN HAYES.
